United States Patent Office

Des. 181,964
Patented Jan. 28, 1958

181,964

FROZEN CONFECTION

Arthur S. Ensler, Scarsdale, and Aaron Friedman, New York, N. Y., assignors to Joe Lowe Corporation, New York, N. Y., a corporation of Delaware

Application October 23, 1956, Serial No. 43,478

Term of patent 14 years

(Cl. D82—2)

We claim:

The ornamental design for a frozen confection, as shown.
